UNITED STATES PATENT OFFICE.

WILLIAM E. KEMP, OF NEW YORK, N. Y.

INTAKE-MANIFOLD.

1,304,987.

Specification of Letters Patent. Patented May 27, 1919.

Application filed November 22, 1917. Serial No. 203,357.

To all whom it may concern:

Be it known that I, WILLIAM E. KEMP, a citizen of the United States, and a resident of the city of New York, in the county of New York and State of New York, have invented certain new and useful Improvements in Intake-Manifolds, of which the following is a specification.

The present invention relates to intake-manifolds for internal combustion engines.

It is commonly known among motor vehicle engineers that about 90% of the carburation difficulties experienced with the present day gasolene or other liquid hydrocarbons is due to the fact that the vaporized fuel has a tendency to condense between the charge forming device and the cylinders of the motor, or in other words in the intake-manifold of the engine. This defect arises from the fact that the area of the passage through the intake-manifold must be dimensioned to be large enough to supply the engine with a combustible mixture of the proper proportions and volume to run the engine at its maximum efficiency. This passage is thus so large that, when the engine demands but a minimum supply, for instance when running idle at say 100 revolutions per minute with no load thereon, the vaporized combustible mixture moves through the manifold on the suction strokes of the pistons at such a reduced velocity that it condenses. The condensed hydrocarbon causes most troubles at low engine speed or at a period when the combustible mixture passing from the carburetor to the motor is idling in the intake-manifold. It is obvious that, when the engine is running with no load or practically with no load, and part of the combustible mixture condenses in the manifold, the engine speed cannot be kept constant or not even nearly constant because the cylinders do not receive a uniform mixture, since the combustible mixture rushing past the condensed hydrocarbon in the intake-manifold is made richer than is desirable.

The main object of the present invention is to provide an intake-manifold, wherein the combustible mixture travels from the carburetor to the engine cylinders at a constant or nearly constant speed, irrespective of the speed of the engine, whereby condensation of the hydrocarbon is prevented.

With these and other objects in view, which will more fully appear as the nature

of the invention is better understood, the same consists in the combination, arrangement, and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

Two of the many possible embodiments of the invention are illustrated in the accompanying drawings, in which:

Figure 1 is a plan view of an intake-manifold constructed in accordance with the present invention; Fig. 2 is a section taken on line 2—2 of Fig. 1; Fig. 3 is a section taken on line 3—3 of Fig. 2; Fig. 4 is a section taken on line 4—4 of Fig. 1, on a larger scale; Fig. 5 is a section taken on line 5—5 of Fig. 1, on a larger scale; Fig. 6 is a section taken on line 6—6 of Fig. 1, on a larger scale; Fig. 7 is a section taken on line 7—7 of Fig. 1, on a larger scale; Fig. 8 is a section similar to the one shown in Fig. 4 of a modified manifold; Fig. 9 is a section taken on line 9—9 of Fig. 8; and Fig. 10 is a section taken on line 10—10 of Fig. 8.

Referring now first to Figs. 1 to 7, inclusive, the numeral 11 indicates an oblong casing, having a detachable front wall 12. Within this casing is disposed centrally a, 90 preferably, cylindrical chamber 13, that communicates through an inlet 14 with the outlet 15 of a carburetor 16 of any suitable construction, only part of said carburetor being shown. The outlet of this carburetor 95 is controlled by a valve 17, in the present case of the butterfly type, for the well-known purpose. The chamber 13 extends a substantial distance above the top of the casing 11, for a purpose hereinafter to be described. 100 Near each end of the casing there is arranged in the same a chamber 18, the outlets 19 of which communicate with the fuel inlet-openings of the cylinders of the engine.

The chamber 13 communicates with the 105 chambers 18 through a plurality of pipes 20, arranged on each side of the chamber 13 in pairs, as clearly appears from Fig. 6 of the drawings, each set of tubes being disposed above another, so that their inlets are 110 arranged in a plurality of parallel planes. The chambers also communicate through a

pair of pipes 21, which are located immediately above the bottom 22 of the casing 11, and lead as close as possible to the outlets 19.

5 Within the chamber 13 is slidably arranged a piston valve 23, the stem 24 of which extends through the head 25 of the said chamber, and is screw-threaded, as shown at 26. With these threads mesh those 10 of a nut 27, that abuts normally against the outer face of the head 25. A weight 28, or its equivalent in the form of a spring, is associated with the piston valve 23, and has a tendency to hold the said piston valve in its 15 lowermost position, in which the outlet of the carbureter communicates through the pipes 21 with the chambers 18, and thus with the fuel inlet-openings of the engine cylinders. The nut 27 serves to adjust the lowermost position of the piston valve 23.

The chambers 13 and 18 do not communicate with the interior of the casing 11. This casing communicates through a pipe 29 with the exhaust passage of the engine, the exhaust 25 gases being led away from the casing through a pipe 30. The casing envelops or jackets the three chambers and also the pipes therein. The exhaust gases are caused to move in a circuitous path around the chambers and the pipes by casting the chambers 30 18 integral with the rear wall 31 of the casing and placing the chamber 13 in contact with the front cover 12 of the said casing. For these reasons the exhaust gases, 35 entering through the pipe 29, move in the direction of the arrows shown in Fig. 3 of the drawings, that is to say they move around the right hand side chamber 18 and between the spaces between the pipes connecting the said chamber with the chamber 13, thence around the last-named chamber and between the pipes connecting the chamber 13 with the left hand side chamber 18, and around the last-named chamber to the 40 pipe 30. In this manner obviously, the combustible mixture traveling through the intake-manifold is pre-heated, for the well-known purpose.

The operation of this device is as follows:—
50 When the engine is at standstill or moves at a slow speed with no load or practically no load, the piston valve in the chamber 13 occupies its lowermost position (Fig. 4), the weight 28, or its equivalent, being sufficient to overcome the suction effect of the pistons on the upper face of the said valve. The combustible mixture is thus drawn into the cylinders through the pipes 21, the other pipes being closed by the piston valve. The 55 cross-section of a pipe 21 corresponds substantially to the effective area of the carbureter outlet when throttled for idling. Obviously, thus the combustible mixture has no chance to condense in the said pipes, as 60 its velocity through the passage from the

carbureter to the engine is substantially constant.

As now the throttle is opened and the engine consequently speeded up, the vacuum above the valve and the pressure below the same increases, due to the increased suction effect of the engine pistons. This results in an automatic rise of the piston valve, which rise is proportionate to the increase in suction of the pistons, whereby the inlets to the pipes 20 will be gradually and successively uncovered. The combined areas of the uncovered pipes will always be equal or nearly equal to the effective cross-section of the carbureter outlet, meaning by effective cross-section the cross-section uncovered by the throttle. When the engine is being slowed down, obviously the reverse conditions will prevail, that is to say the suction above the valve will decrease, causing the same to descend and to successively and gradually close the pipes 20. From the foregoing it appears that the active cross-section of the intake-manifold is automatically varied in proportion to the speed of the engine and the effective area of the carbureter outlet, whereby the combustible mixture flows through the said manifold at a constant or nearly constant speed, irrespective of the speed of the engine.

95 The salient feature of this invention lies in the provision of a group of pipes of relatively small area, the aggregate areas of the pipes constituting the group being sufficient to supply the engine with the required volume of combustible mixture to run it at its maximum efficiency, provision being made for cutting off certain pipes as the demand for fuel decreases, this cutting off of these pipes effecting a decrease of the area of the manifold, so that the speed of combustible mixture is constant or substantially constant as it travels through the same.

100 The advantages of eliminating condensation are, besides the one mentioned, manifold, the principal ones being the ease with which the engine may be started when cold, and the extreme flexibility.

105 A modification of the invention is illustrated in Figs. 8 to 10, inclusive, differing from the one above described in that, instead of the chambers 18, there are formed in proximity to the outlets 19 chambers 33, which do not extend, as the chambers 18, throughout the height of the casing 11, but are disposed substantially above the said casing. The pipes 20 and 21 lead in this case from the chamber 13 to the bottoms 110 of the chambers 33, their outlets being thus 115 located as near as possible to the intake-openings of the cylinders of the engine. Instead of a weight, a spring 35 is made use of 120 in this device, as an alternative.

125 The operation of this device is in all re- 130

spects the same as of that above described, the only difference being that the combustible mixture has less chance to condense, for the reason that the outlets of the pipes 5 in the manifold terminate in close proximity to the engine cylinders.

It is obvious that, while herein the invention has been described in connection with the intake-manifold of an internal combustion engine, the same may be applied generally to vary the cross-section of conduits throughout their lengths, irrespective of the nature of the fluid flowing therethrough. Attention is called to the fact that, in such 15 cases, the cross-section may be either varied by manually operated means, or automatically by the difference of pressure at the ends of the conduit.

What I claim is:—

20 1. An intake-manifold for internal combustion engines, comprising a casing having a fuel inlet and fuel outlets, a chamber extending throughout the height of said casing communicating with each of said fuel outlets, a plurality of conduits extending from said inlet chamber to each of said outlet chambers, and a weighted valve within 25 said inlet chamber tending to close said con-

duits but actuated under suction above the same and pressure below the same, thereby 30 automatically opening and closing said conduits progressively and in succession in proportion to the speed of the engine, both the suction and pressure being induced by the 35 operation of the engine.

2. An intake-manifold for internal combustion engines, comprising a casing having a fuel inlet and fuel outlets, a chamber extending throughout the height of said casing communicating with each of said fuel outlets, a plurality of conduits extending from said inlet chamber to each of said outlet chambers, a weighted valve within said inlet chamber tending to close said conduits but actuated under suction above the same 40 and pressure below the same, thereby automatically opening and closing said conduits 45 progressively and in succession in proportion to the speed of the engine, both the suction and pressure being induced by the operation of the engine, and means for adjusting the lowermost position of said valve.

Signed at New York, in the county of New York, and State of New York, this 14th day of November, A. D. 1917.

WILLIAM E. KEMP.
